ELECTRONIC AMPLIFIER CONTROLLED RELAY

Willis H. Gille, St. Paul, and William J. Field and Theodore J. Wilson, Minneapolis, Minn., assignors to Minneapolis-Honeywell Regulator Company, Minneapolis, Minn., a corporation of Delaware

Application November 18, 1942, Serial No. 466,009

7 Claims. (Cl. 175—335)

1

This invention relates to electronic amplifiers, and particularly to amplifiers adapted for use in control systems of the type wherein a device is controlled in accordance with an electrical signal produced by means responsive to a controlling condition.

An object of the present invention is to provide an improved amplifier circuit for use in a control system wherein it is desired to operate a load device either intermittently for periods of varying lengths or continuously, dependent upon the magnitude of an electrical signal.

Another object of the present invention is to provide an improved amplifier circuit for use in motor control systems of the type shown in the co-pending application of Willis H. Gille, Serial No. 447,989, filed June 22, 1942, and in the co-pending joint application of Willis H. Gille, Albert P. Upton and William J. Field, Serial No. 466,008, filed November 18, 1942.

A further object of the present invention is to provide an improved amplifier circuit for controlling the operation of a relay in accordance with a variable condition. A still further object is to provide, in such an amplifier, the combination of a circuit operated by the relay and effective to decrease the sensitivity of the amplifier so as to cause intermittent operation of the relay, and a feedback circuit independent of the relay and effective to increase the sensitivity of the amplifier.

Other objects and advantages of our invention will become apparent from a consideration of the appended specification, claims and drawing, in which:

Figure 1 is an electrical wiring diagram of an amplifier circuit embodying the principles of our invention.

Figure 2 is a somewhat diagrammatic representation of a control system wherein the amplifier circuit of Figure 1 may advantageously be used.

Figure 3 is a graphical representation of the operation of the amplifier circuit of Figure 1, and

Figure 4 is a graphical representation of the operation of a different portion of the amplifier circuit of Figure 1.

Referring now to Figure 2, there is shown a system for controlling the movements of the rudder of an aircraft in accordance with the deflection of a directional gyroscope, diagrammatically indicated at 10, from a normal position. The gyroscope 10 is constructed, in a manner well known in the art, so as to rotate a shaft 11 whenever the aircraft on which the gyroscope is mounted

changes its direction. Fixed on the shaft 11 is a slider 12, which cooperates with a slidewire resistance 13. The slider 12 and the resistance 13 together form a control potentiometer 14.

5 The resistance 13 is connected in an electrical network 15, of the Wheatstone bridge type. The network 15 also includes a slidewire resistance 16, with which is associated a slider 17. The resistance 16 and slider 17 together form a follow-up potentiometer 18. The network 15 is supplied with electrical energy from a transformer secondary winding 14, whose terminals 20 and 21 are connected through conductors 22 and 23, respectively, to the left and right terminals of resistances 13 and 16. The sliders 12 and 17 form the output terminals of the network 15.

10 The slider 17 is fixed on a shaft 24 for rotation therewith. The shaft 24 also carries a pulley 25 and a gear 26. A cable 27 runs over the pulley 25. This cable 27 may be the conventional control cable used in aircraft for positioning the rudder.

15 The gear 26 engages a pair of gears 30 and 31, which are fixed on shafts 33 and 32, respectively. The shaft 33 is connectable, through an electrically operable clutch device schematically indicated at 34, to a driving shaft 35. Similarly, the shaft 32 is connectable by an electrically operable clutch device schematically indicated at 36 to a driving shaft 37. The shafts 35 and 37 carry gears 38 and 39, respectively, which mate with each other so that the shafts 35 and 37 rotate in opposite directions. The gear 38 operatively engages a gear 41 which is driven by a continuously running motor 42.

20 The motor 42 may be supplied with electrical energy from any suitable source, as for example a battery 43. An energizing circuit for motor 42 may be traced from the upper terminal of battery 43 through conductors 44 and 45, motor 42, a conductor 46, ground connections 47 and 48, and a conductor 49 to the lower terminal of battery 43.

25 The battery 43 also supplies electrical energy to a converter 51, which may be of any conventional type, and serves to supply alternating electrical energy to an amplifier 52, which is described in detail in Figure 1. The direct current input circuit for converter 51 may be traced from the upper terminal of battery 43 through conductors 44 and 53, converter 51, a conductor 54, ground connections 55 and 48, and conductor 49 to the lower terminal of battery 43. The converter 51 supplies alternating electrical energy through conductors 56 and 57 to power input terminals 58 and 59 of amplifier 52.

The slider 12 is connected through a shielded conductor 61 to an input terminal 62 of amplifier 52. The slider 17, which serves as the other output terminal of network 15, is connected through a conductor 63 to ground at 64. The other input terminal 65 of amplifier 52 is grounded as at 66.

As explained in greater detail hereinafter in connection with the description of Figure 1, the amplifier 52 selectively controls the conductivity of energizing circuits for the electrically operated clutches 34 and 36. The energizing circuit for clutch 34 may be traced from the upper terminal of battery 43 through a conductor 60, a terminal 67 of amplifier 52, an internal connection in amplifier 52, a terminal 68, a conductor 69, clutch 34, a conductor 70, ground connections 71 and 48, and conductor 49 to the lower terminal of battery 43. The energizing circuit for clutch 36 may be traced from the upper terminal of battery 43 through a conductor 73, a terminal 74 of amplifier 52, an internal connection in amplifier 52, a terminal 75, a conductor 76, clutch 36, a conductor 77, ground connections 78 and 48, and conductor 49 to the lower terminal of battery 43.

Suitable switch means may be provided for shutting down the entire system when not in use. Also limit switch means may be provided for selectively preventing energization of one or the other of the clutches when the follow-up potentiometer, or the rudder, reaches the end of its range of travel. A suitable switching arrangement is shown, for example, in the Gille application, Serial No. 447,989, dated June 22, 1942, previously mentioned.

Referring to Figure 1, there are shown the details of the amplifier circuit 52. This amplifier comprises a first preliminary voltage amplification stage 80, a second preliminary voltage amplification stage 81, and a final power amplification stage 82. The amplifier 52 also includes a rectifier circuit 83 for supplying power to the preliminary stages 80 and 81 and to provide suitable biasing potentials for the second stage 81 and the final stage 82.

The first amplification stage 80 includes an electric discharge device, shown as a triode 84, which may be, for example, one half of a twin triode of the type known commercially as type 7F7. The triode 84 includes an anode 85, a control electrode 86, a cathode 87, and a heater filament 88.

A resistance 90 is connected across the input terminals 62 and 65 of amplifier 52, so that any signal potential occurring between those terminals causes a corresponding current flow through resistance 90. The resistance 90 is provided with an adjustable tap 91 which serves in a well known manner to control the gain of the amplifier 52.

The input circuit of amplifier stage 80 may be traced from control electrode 86 through a shielded conductor 92, tap 91, a portion of resistance 90, terminal 65, and ground connections 66 and 93 to cathode 87. The output circuit of stage 80 may be traced from a conductor 94, which serves as the positive terminal of the output circuit power supply, through a load resistance 95, anode 85, cathode 87, to ground at 93, the ground connection serving as the negative terminal of the output circuit power supply.

The second amplifier stage 81 includes a triode 96 having an anode 97, a control electrode 98, a cathode 99, and a heater filament 100. The triodes 84 and 96 may be, for example, the two halves of a single 7F7 twin triode. The input cir-

cuit of the stage 81 may be traced from control electrode 98 through a resistance 101, a resistance 102, a resistance 103, and a condenser 104 in parallel therewith, a conductor 105, a resistance 106 and a condenser 107 in parallel therewith, and ground connections 108 and 109 to cathode 99. The output circuit of stage 81 may be traced from positive supply terminal 94 through a load resistance 111, anode 97, cathode 99, to ground at 109.

A pair of resistances 112 and 113 are connected between positive power supply terminal 94 and ground at 114. The resistance 113 is provided with an adjustable tap 115, and the latter is connected through a resistance 116 to the lower terminal of resistance 102 in the input circuit of stage 81. This connection serves to provide a positive bias potential for this input circuit. An additional positive bias potential may be applied to this input circuit through a connection which may be traced from the lower terminal of resistance 102 in the input circuit through a conductor 117, either through conductor 118, contact 119, and switch arm 120 to a conductor 124, or through conductor 121, contact 122 and switch arm 123 to conductor 124, and thence through a variable resistance 125 and a fixed resistance 126 to a conductor 120 in the rectifier circuit 83 which is positive with respect to ground. Variations in the potential of anode 85 caused by variations in the output current of the stage 80 are coupled to the input circuit of stage 81 through a blocking condenser 127 and a conductor 128.

The final power amplification stage 82 includes a twin triode 130, which may be of the type commercially known as type 7N7. The twin triode 130 includes two separate triodes 131 and 132. The triode 131 includes an anode 133, a control electrode 134, a cathode 135, and a heater filament 136. The triode 132 includes an anode 137, a control electrode 138, a cathode 139, and a heater filament 140.

The power amplification stage 82 includes a common input circuit for both the triodes 131 and 132. This common input circuit may be traced from either control electrode 134 or control electrode 138 through a conductor 142, a fixed resistance 143, tap 144, a portion of the resistance 145, and ground connections 146 and 147 to cathodes 135 and 139. Variations in the potential of anode 97 caused by variations in the output current of the second amplifier stage 81 are transmitted to the common input circuit of the final stage 82 through a blocking condenser 148 and a conductor 149 to conductor 142 in the common input circuit. The resistance 145 is so connected to the rectifier circuit 83 that the tap 144 is negative with respect to ground. The setting of tap 144 with respect to resistance 145 therefore determines a negative bias potential applied to the common input circuit of final stage 82, and hence the normal current flow in the output circuits of that stage.

The output circuit of final stage 82 is divided into two branches, each of which includes one of the triodes 131 and 132. Both branches of the output circuit of stage 82 are supplied with alternating electrical energy from a secondary winding 151 of a transformer 152. The transformer 152 also includes a primary winding 153 and two additional secondary windings 154 and 155.

The upper branch of the output circuit of final stage 82 may be traced from the upper terminal of secondary winding 151 through a winding 156 of a relay 158 and a condenser 157 connected in

parallel with winding 156, anode 133, cathode 135, ground connections 147 and 108, resistance 106 and the parallel condenser 107, to a mid-point tap 160 on transformer secondary winding 151. The lower branch of the final stage output circuit may be traced from the lower terminal of secondary winding 151 through a winding 161 of a relay 162 and a condenser 163 in parallel with the winding 161, anode 137, cathode 139, ground connections 147 and 108, and resistance 106 and the parallel condenser 107 to mid-point tap 160 on winding 151.

From the foregoing, it should be apparent that the two branches of the output circuit of final stage 82 may be conductive on opposite half cycles of the alternating energy supplied by the winding 151. That is, the triode 131 may be conductive during the half cycles when the upper terminal of winding 151 is positive with respect to the center tap 160, while the triode 132 may be conductive during the half cycles when the lower terminal of secondary winding 151 is positive with respect to center tap 160. The secondary winding 154 of transformer 152 is connected through the terminals 20 and 21 to the network 15 (see Figure 2). Therefore, any signal which appears between the output terminals of network 15 is of the same frequency as the energy supplied to the final output stage 82. In accordance with the well known characteristics of alternating current bridge circuits, it will be understood that the time phase of such a signal depends upon the direction of unbalance of the network 15. If the phase of the signal is such that the control electrodes 134 and 138 are positive when the upper terminal of secondary winding 151 is positive, the current flow through triode 131 is increased above the normal value determined by the setting of tap 144 on resistance 145, while if the phase of the signal is such that the control electrodes 134 and 138 are positive when the lower terminal of secondary winding 151 is positive, then the current flow through the triode 132 is increased.

Condensers 157 and 163 operate to maintain energization of the relay windings 156 and 161, respectively, over a period longer than the half cycles during which the triodes associated with the respective relays are conductive. During the half cycle when a particular triode is conductive, the triode supplies the current flowing through the relay winding and also charges the condenser. During the half cycle when the triode is nonconductive, the condenser discharges through the relay winding, thereby maintaining the current flow.

Relay 158 includes, in addition to the winding 156, the switch arm 120, previously mentioned, and a switch arm 165 which cooperates with a stationary contact 166. Both the switch arms 120 and 165 are biased by means not shown, to the circuit opening position and are moved to circuit closing position upon sufficient energization of relay winding 156.

The relay 162 similarly includes, in addition to winding 161, the switch arm 123 previously mentioned, and a switch arm 167 which cooperates with a stationary contact 168. Both switch arms 123 and 167 are biased to the circuit opening position and are moved to their circuit closing position upon sufficient energization of winding 161.

The rectifier circuit 83 which supplies unidirectional electrical energy to the output circuits of stages 80 and 81 is energized from secondary winding 155 of transformer 152. This rectifier

circuit includes a twin diode 170, which may be of the type commercially known as type 7Y4. The twin diode 170 includes a first diode 171 having an anode 172, a cathode 173, and a heater filament 174. The second diode is generally indicated at 175, and includes an anode 176, a cathode 177, and a heater filament 178. The rectifier circuit is of the well known full wave type. On the half cycles when the upper terminal of secondary winding 155 is positive, current flows therefrom through anode 172 and cathode 173 of diode 171 to a conductor 180. On the half cycles when the lower terminal of secondary winding 155 is positive, current flows therefrom through anode 176 and cathode 177 of diode 175 to conductor 180. The current supplied to the output circuits of stages 80 and 81 passes from conductor 180 through a filter network comprising a choke coil 181 and condensers 182 and 183 connected between the opposite terminals of the choke coil 181 and ground. After passing through the filter network, the current flows along conductor 184 to conductor 94 which serves as the positive power supply terminal for the output circuits of stages 80 and 81. The various ground connections serve as the negative power supply terminal for these output circuits. The current supplied by the rectifier circuit 83 flows through the various output circuits and ground connections to ground connection 146, and thence through resistance 145, and conductors 135 and 196 to a center tap 187 on transformer secondary winding 155. It should be noted that the direction of current flow through resistance 145 is such as to make its left terminal positive with respect to its right terminal, as indicated by the legend in the drawing. A filter condenser 188 is connected between conductors 180 and 186.

The heater filaments 88, 100, 136, 140, 174 and 178 may be connected to any suitable source of electrical energy (not shown).

In order to aid those skilled in the art in constructing an amplifier in accordance with our invention, the following table is appended, giving values of the various resistances and condensers used in one embodiment of our invention:

	Reference Character	Quantity
50	90.....	10,000 ohms.
	95.....	1/2 megohm.
	101.....	1/2 megohm.
	102.....	1/2 megohm.
	103.....	0.1 megohm.
	104.....	.05 microfarad.
	106.....	500 ohms.
	107.....	.05 microfarad.
55	111.....	1/2 megohm.
	112.....	1/2 megohm.
	113.....	1 megohm.
	116.....	1/2 megohm.
	125.....	1/2 megohm.
	126.....	0.1 megohm.
	127.....	.05 microfarad.
60	143.....	1/2 megohm.
	145.....	.05 megohm.
	148.....	.05 microfarad.
	157, 163.....	1 microfarad.
	181.....	4,000 ohms D. C. resistance; 30 henries inductance.
65	182.....	1/2 microfarad.
	183.....	.05 microfarad.
	188.....	.05 microfarad.

Operation

When the sliders 12 and 17 are in the positions shown in Figure 2, the network 15 is balanced and no signal potential is impressed on the input terminals 62 and 65 of amplifier 52. Under these conditions, neither of the relays 158 or 162 is

energized, and hence neither of the clutches 34 and 36 is energized. The shaft 24, the follow-up slider 17 and the rudder of the aircraft therefore remain stationary.

In this specification, either of the relay windings 156 or 161, or either of the relays 158 and 162, may be described as energized whenever the current flow through the winding in question is sufficient to move the associated switch arms to, or to hold them in, their attracted position. The windings or relays may be described as deenergized whenever the current flow is such that the switch arms are in their retracted position.

If the aircraft deflects from the course which it is desired to maintain, the gyroscope 10 operates the slider 12 across the resistance 13. Let it be assumed that a deflection takes place in a direction such that slider 12 is moved to the left across resistance 13. Slider 12 thereby assumes a potential nearer to that of input terminal 20 than the potential of slider 17. A signal potential is therefore impressed on the input terminals of amplifier 52, and the phase of this signal is the same as that which would be obtained if bridge input terminal 20 were connected to amplifier input terminal 62, and bridge input terminal 21 were connected to amplifier input terminal 65. Let it be assumed that the amplifier 52 reacts to a signal of this phase by causing energization of winding 156 of relay 158. Energization of winding 156 causes switch arm 165 to engage contact 166, thereby completing the energizing circuit for clutch 34. It may be assumed that motor 42 rotates in such a direction that when clutch 34 is energized, shaft 24 rotates in a counter-clockwise direction, thereby moving slider 17 to the left along resistance 16. As soon as this motion of slider 17 has progressed far enough so that its potential equals that of slider 12, the signal impressed on the input terminals of amplifier 52 is reduced to zero, thereby causing deenergization of clutch 34 and stopping of the shaft 24.

In a similar manner, it may be observed that if the slider 12 moves to the right from the position shown in the drawing, it thereby attains a potential closer to that of bridge input terminal 21 than that of slider 17. A signal potential is thereby impressed on the input terminals of amplifier 52. The phase of this signal is the same as that which would be obtained if terminal 21 were connected to amplifier input terminal 62 and terminal 20 were connected to amplifier input terminal 65. This signal is therefore of a phase opposite to that obtained under the conditions just discussed. This signal causes the amplifier to energize winding 161 of relay 162, thereby causing switch arm 167 to engage contact 168 and complete the energizing circuit for clutch 36. Energization of clutch 36 causes shaft 24 to be rotated in a direction opposite to that caused by energization of clutch 34. The shaft 24 therefore moves clockwise, driving the slider 17 to the right along resistance 16 in a direction to rebalance the network 15.

If the shaft 24 is rotating too rapidly as the slider 17 approaches the point at which the network 15 will be rebalanced, the slider 17 may overshoot the balance point because of the inertia of the moving parts of the system. If such overshooting occurs, a hunting condition is set up, wherein the slider 17 oscillates back and forth about the balance point. In other words, the slider "hunts" for the balance point without finding it. In order to prevent the establishment of such hunting conditions, we have provided means

for establishing a range of positions extending a short distance on either side of the balance point, wherein the slider 17 may come to rest, even though the bridge circuit 15 may be slightly unbalanced. This range of positions is known as the "dead spot." Means are provided for adjusting the width of this range of position, and this means is referred to as the "dead spot" or sensitivity adjustment. This "dead spot" is of course effective with respect to either the control slider 12 or the follow-up slider 17. We have also provided means for further reducing the tendency of the system to "hunt" by controlling the average rate of operation of the shaft 24 in accordance with the magnitude of the unbalance of the network 15. In our system, if the control slider 12 moves beyond the "dead spot," the amplifier circuit causes intermittent energization of one of the clutches 34 and 36, the length of the periods of energization being modulately increased as the distance of the slider 12 from the dead spot increases. After the slider 12 has passed through a second range of positions, hereinafter referred to as the intermittent range, the particular clutch selected in accordance with the direction of unbalance of the bridge circuit is continuously energized. We have provided in our circuit means for determining the amount of unbalance of the bridge circuit 15 required to cause continuous energization of one of the clutches.

In order to understand the manner in which this operating characteristic of the amplifier and system is obtained, it is necessary first to consider the input potential-output current characteristic of the second amplification stage 81. This characteristic is completely described in detail in the co-pending application of Willis H. Gille, Serial No. 447,989, filed June 22, 1942, previously referred to. Therefore it will be mentioned but briefly in the present application. Referring to Figure 3, there is shown at A the normal input voltage-output current characteristic of the triode 96. Because of the high resistance (1/2 meg-ohm) 101 connected in series with the control electrode 98, and because the input circuit is biased positively through resistance 116, tap 115, and resistance 113, the stage 81 as a whole does not have the same characteristic as the triode A. The positive biasing voltage causes a current to flow through resistance 101 and from the control electrode to the cathode in the triode 96. This current, flowing through resistance 101, produces thereacross a potential drop which effectively maintains the control electrode 98 at a value only slightly positive with respect to the cathode 99, whenever the resultant voltage impressed on the input circuit at the left terminal of resistance 101 is positive. Therefore, the stage 81 as a whole has an input voltage-output current characteristic which follows the curve A until a slightly positive value of input potential is reached, after which further increases in the input potential cause no change in the output current. The characteristic of the stage as a whole therefore follows the curve B when the input potential is negative or just slightly positive, and thereafter abruptly changes and follows the straight line B of Figure 3.

Four different potentials are present on the input circuit of the stage 81 having the characteristic as described above. The first of these four potentials is the biasing potential, which is positive with respect to cathode 99, and whose magnitude is determined by the position of tap 115 with respect to resistance 113. In Figure 3,

this positive biasing potential is assumed to have a magnitude indicated by the distance C.

The second potential impressed on the input circuit of stage 81 is the alternating signal potential which is transmitted to the input circuit from the output circuit of stage 80 through the blocking condenser 127. For the present discussion of the operation of this system, the signal potential is assumed to have a constant amplitude, as indicated by the curve D in Figure 3.

By reference to Figure 3, it may be seen that the positive biasing potential C determines the amplitude of the alternating input signal necessary to cause a variation in the output current of stage 81. Therefore the magnitude of the positive biasing potential C determines the amount of unbalance of bridge circuit 13 necessary to start operation of shaft 24. Hence the adjustment of tap 115 with respect to resistance 113 controls the width of the "dead spot" of the system.

Consider for the moment, the variations in the output current of the stage 81 which would be caused by the signal D acting in conjunction with the biasing voltage C, with no other factors influencing the operation of the stage 81. Such variations in output current are illustrated by the curves marked F in Figure 3. The corresponding variations in the input potential and hence in the output current of one of the triodes in the final stage 82, are shown at G in Figure 4. The relays 158 and 162 have the characteristic common to such devices, that a predetermined value of current, which may be that indicated by the line H in Figure 4, is necessary to cause the relays to move their associated switch arms to their attracted positions, but a smaller value of current is sufficient to maintain the switch arms in their attracted positions. The minimum value of current which may maintain the relays in their energized condition is indicated by the line K in Figure 4. From an inspection of Figure 4, it may be readily determined that the current values indicated by the loops G are not sufficient to cause energization of the relay.

The third of the four potentials impressed on the input circuit of stage 81 is a unidirectional negative potential developed across resistance 106 and condenser 107 by the current flowing in the final output stage 82, and fed back through resistance 103 and condenser 104 to the input circuit of stage 81. This potential opposes the positive biasing voltage, and hence tends to increase the sensitivity of the amplifier circuit as the current flowing in the output stage 82 increases. This potential which is hereinafter referred to as the feedback potential is shown at E in Figure 3. This feedback potential exists at all times when either of the triodes in the output stage 82 is conductive, regardless of whether the current flow through that stage is sufficient to cause operation of either of the relays 158 or 162. It is indicated in Figure 3 that the feedback potential E does not exist until a signal voltage is impressed on the input circuit of the final stage 82, from which it might be inferred that the triodes of the final stage 82 are biased to cut off. It should be understood that it is not necessary to our invention that the triodes of the final stage 82 be biased to cut off. In fact, they are preferably not biased to cut off. Therefore, the negative feedback voltage will have a small residual value at all times, even when no signal is impressed on the output stage. This residual value

is ineffective in the operation of our system, since it is opposed by a part of the positive biasing voltage. Both this residual feedback voltage and the opposing portion of the positive biasing voltage have been omitted from Figure 3 as an aid to the clarity of that figure.

The time constant of the feedback circuit and the inductive effect of the output stage plate circuit cooperate to delay the transmission of the feedback pulse to the input circuit of stage 81 sufficiently so that its effect is not felt until the latter part of the negative swing of the signal voltage during which the feedback pulse is produced. The feedback potential impulse due to the first cycle of signal D, for instance, appears at E1 in Figure 3, the second impulse appearing at E2.

During the second cycle of signal D, after the feed-back potential E is effective, the net input potential is represented by the curve L in Figure 3, and has a value determined, by the sum of the magnitudes of the signal potential D and the feedback potential E. The variation in the output current of the stage 81 during the second cycle, which is caused by the input wave L, are indicated by the curve M in Figure 3. This curve M should be contrasted with the corresponding curve F which indicates the current variation which would occur if the feedback potential E were not provided. The corresponding current variation in the output circuit of the final stage 82 is shown by the curve N in Figure 4. It should be noted that in the second cycle the curve N in Figure 4 increases above the line H, and therefore causes energization of the relay and movement of its contacts to their attracted position. The condenser in parallel with the relay winding maintains energization of the relay by maintaining the current flow therethrough as indicated along the dotted line P of Figure 4. It may therefore be seen that the energization of the relay continues until the current flow therethrough has decreased below the line K, which occurs somewhat more than one cycle after the relay is first energized.

The fourth of the four potentials impressed on the input circuit of stage 81 is controlled by the switch arms 120 and 123 of the relays 158 and 162. It may be seen that the movement of either switch arm 120 or 123 into engagement with its associated contact completes a circuit from the input of stage 81 through the resistances 125 and 126 to the conductor 180, which is connected to the positive terminal of the output voltage supply of stage 81. This circuit therefore impresses an additional positive potential on the input circuit of stage 81, which is the fourth potential previously described.

The application of the full value of this fourth potential to the input circuit of stage 81 is delayed because of the time required to charge condensers 104 and 107 to correspond to the new potential value maintained across their terminals. The fourth potential applied to the input circuit of stage 81 therefore varies substantially as indicated by the curve Q in Figure 3. This potential introduces an additional component into the curve L which represents the net input potential of the stage 81. The magnitude of this potential Q is adjustable by variation of the setting of the resistance 125. In the example shown, the magnitude of this potential is sufficient to overcome the influence of the signal D and the negative feedback potential E, and causes the net input potential L to change to a value so that it is no

longer effective to cause a variation in the output current of the stage 81. During the third cycle of the signal D, there is therefore no change in the current flow of the output stage 82 and hence the relay becomes deenergized as soon as the curve P passes below the straight line K. If the input signal D becomes sufficiently large as compared with the potential Q, a condition may be obtained wherein the relay will be continuously energized. It may therefore be seen that the adjustment of resistance 125 determines the amount of unbalance of bridge circuit 15 necessary to cause continuous energization of the relays in the output stage 82.

Movement of tap 144 along resistance 145 determines the negative biasing potential applied to the input circuit of the final stage 82. If this bias is made increasingly negative, the amount of current obtained from the output stage for a given value of input signal is made smaller, thereby decreasing the sensitivity of the system. On the other hand, increasing this bias in a negative sense decreases that portion of the positive half cycle during which the current flow through the tube is sufficient to cause operation of the relay. The negative bias therefore has the effect of decreasing the possibility of false operation of one of the relays due to a phase shift in the incoming signal such as may be caused by the fact that the impedances in the bridge and amplifier circuits are not purely resistive. The negative bias also serves to increase the stability of the triodes in the final stage by the introduction of impedance in their input circuits. The tap 144 should be set to give some compromise value of biasing potential which is experimentally found to give satisfactory sensitivity and at the same time to produce a substantially stable circuit, as far as the phase shift effects are concerned.

It has been shown in the preceding example, that with a signal of a given constant amplitude, the relay selected is energized intermittently for periods having a length of approximately one cycle of the incoming signal. In a circuit using the principles described, it has been found that if the magnitude of the input signal is gradually increased, the periods of energization of the relays increase substantially in steps of one cycle. For example, as the incoming signal is gradually increased from zero, when it reaches approximately the amplitude indicated by the curve D, the selected relay is energized for a period of substantially two cycles, and upon further increase the period of energization increases to a period of substantially three cycles, and so on. It may therefore be said that over a given range of signals, the duration of the periods of intermittent energization of the relays is modulatingly increased in accordance with the value of the signal.

While we have shown and described a preferred embodiment of our invention, other modifications thereof will readily occur to those skilled in the art, and we therefore wish our invention to be limited only by the appended claims.

We claim:

1. Control apparatus, comprising in combination, relay means including an electrical winding and control means operated thereby upon the occurrence of a current flow through said winding in excess of a predetermined value, electronic amplifier means responsive to an alternating electrical signal potential of variable magnitude for controlling the current flow through said

winding, means including a feedback circuit associated with said amplifier means to increase the sensitivity thereof in accordance with the magnitude of the current flow through said winding, and means effective upon operation of said control means by said winding to decrease the sensitivity of said amplifier means by an amount greater than the increase produced by said sensitivity-increasing means, and thereby to cause intermittent energization of said winding.

2. Control apparatus, comprising in combination, relay means including an electrical winding and control means operated thereby upon the occurrence of a current flow through said winding in excess of a predetermined value, electronic amplifier means responsive to an alternating electrical signal potential of variable magnitude for controlling the current flow through said winding, means including a feedback circuit for

15 applying a unidirectional potential to said amplifier means to increase the sensitivity thereof in accordance with the magnitude of the current flow through said winding, and means effective upon operation of said control means by said winding to decrease the sensitivity of said amplifier means by an amount greater than the increase produced by said sensitivity-increasing means, and thereby to cause intermittent energization of said winding.

3. Control apparatus, comprising in combination, means for producing an alternating electrical signal potential of variable magnitude, relay means including an electrical winding and switch contacts closable thereby upon the occurrence of a current flow through said winding in excess of a predetermined value, electronic amplifier means responsive to said signal potential for controlling the current flow through said winding, means including a feedback circuit as-

30 sociated with said amplifier means to increase the sensitivity thereof in accordance with the magnitude of the current flow through said winding, and means including a circuit completed by closure of said contacts and effective to decrease

35 the sensitivity of said amplifier means by an amount greater than the increase produced by said sensitivity-increasing means, and thereby to cause intermittent energization of said winding.

4. Control apparatus, comprising in combination,

50 means for producing an alternating electrical signal potential of variable magnitude, relay means including an electrical winding and control means operated thereby upon the occurrence of a current flow through said winding in excess

55 of a predetermined value, electronic amplifier means responsive to said signal potential for controlling the current flow through said winding, circuit means in said amplifier means for controlling the sensitivity thereof in inverse relation

60 to the magnitude of a positive potential applied to said circuit means, feedback circuit means associated with said amplifier means to apply to said circuit means a negative potential varying in accordance with the magnitude of the cur-

65 rent flow through said winding, and means effective upon operation of said control means by said winding to apply to said circuit means a positive potential greater than the negative potential applied by said feedback circuit means, and thereby to cause intermittent energization of said winding.

5. Control apparatus, comprising in combination, relay means including an electrical winding and switch contacts closable thereby upon the occurrence of a current flow through an alter-

nating electrical winding in excess of a predetermined value, electronic amplifier means responsive to said signal potential of variable magnitude for controlling the current flow through said winding, circuit means in said amplifier means for controlling the sensitivity thereof in inverse relation to the magnitude of a positive potential applied to said circuit means, feedback circuit means associated with said amplifier means to apply to said circuit means a positive potential varying in accordance with the magnitude of the current flow through said winding, and means including a circuit completed by closure of said contacts to apply to said circuit means a positive potential greater than the negative potential applied by said feedback circuit means, and thereby to cause intermittent energization of said winding.

6. Electrical control apparatus, comprising in combination: means for producing an alternating electrical signal potential of variable magnitude; a device to be operated in accordance with the magnitude of said signal; electrical winding means for controlling the operation of said device; electronic amplifier means responsive to said signal potential for controlling the flow of current through said winding means, said amplifier means including a preliminary stage comprising an electrical discharge device and a later stage comprising two electrical discharge devices connected in phase opposition, each said discharge device having an anode, a cathode, and a control electrode, an input circuit for each discharge device including its control electrode and cathode, an output circuit for each discharge device including its anode and cathode, the output circuits of said two discharge devices in said later stage having a common portion, an impedance, means connecting said impedance in said common portion so as to produce across said impedance a unidirectional potential substantially proportional to the current flowing in said common portion, and means in the input circuit of said preliminary stage for controlling the sensitivity

- of said amplifier means in inverse relation to the magnitude of a positive potential applied to the input circuit of said preliminary stage; feedback circuit means for applying said unidirectional potential to said preliminary stage input circuit with its polarity opposed to said positive potential to increase the sensitivity of said amplifier means; and means for coupling said winding means to the output circuits of said later stage.
- 5 7. Control apparatus, comprising in combination, relay means including an electrical winding and control means operated thereby upon the occurrence of a current flow through said winding in excess of a predetermined value, electronic amplifier means responsive to an alternating electrical signal potential of variable magnitude for controlling the current flow through said winding, means including a feedback circuit associated with said amplifier means to increase the sensitivity thereof in accordance with the magnitude of the current flow through said winding, and impedance means in said feedback circuit effective to delay said increase in sensitivity for a time substantially equal to one cycle of said signal potential.
